Primary Examiner — Jennifer L Rempfer*Assistant Examiner* — Michelle Marquart Christeon(74) *Attorney, Agent, or Firm* — Woodard, Emhardt, Henry, Reeves & Wagner, LLP(57) **CLAIM**

The ornamental design for an endoscope handle as shown and described.

DESCRIPTION

FIG. 1 is a front, right, perspective view showing my new design;

FIG. 2 is a back, left perspective view thereof;

FIG. 3 is a right side view thereof;

FIG. 4 is a back side view thereof;

FIG. 5 is a left side view thereof;

FIG. 6 is a front view thereof;

FIG. 7 is a top view thereof; and,

FIG. 8 is a bottom view thereof.

The broken lines illustrate portions of the endoscope handle that form no part of the claimed design.
